Primary Examiner — Richard E Chilcot(74) *Attorney, Agent, or Firm* — Edmonds & Nolte, P.C.(57) **CLAIM**

The ornamental design for a lower set insert for a downhole plug for use in a wellbore, as shown.

DESCRIPTION

FIG. 1 is a perspective view of a lower set insert for a down-hole plug;

FIG. 2 is a top plan view thereof;

FIG. 3 is a side plan view thereof; and,

FIG. 4 is a bottom plan view.

The broken lines shown in the drawings are for illustrative purposes only and form no part of the claimed design.
